HEAT TRANSFER APPARATUS
 William H. Armstrong, 197 Sandwich St.,
 Plymouth, Mass. 02360
 Filed July 29, 1964, Ser. No. 385,978
 7 Claims. (Cl. 165—56)

This invention relates to heat transfer apparatus.

One object of my invention is to provide heat transfer apparatus which is adaptable for use with stock panels commonly used to assemble ceilings.

Another object is to provide such apparatus that may be formed of two duplicate sections each of which may be made integral.

A further object is to so construct said apparatus that it can readily be assembled into contact with a hot water conduit or other temperature modifying member and also assembled with said stock ceiling panels as part of a simple continuing operation.

A still further object is to provide such apparatus that can be manufactured economically and in large quantities and is so constructed that it takes final form, ready for use, by a simple production operation.

The foregoing and other objects which will appear as the nature of the invention is better understood, may be accomplished by a combination and arrangement such as is disclosed by the drawing. The nature of the invention is such as to render it susceptible to various changes and modifications, and therefore, I am not to be limited to the construction disclosed by the drawing, nor to the particular parts described in the specification; but am entitled to all such changes therefrom as fall within the scope of my claims.

In the drawing:

FIG. 1 is a perspective view of my heat transfer apparatus assembled with two ceiling panels and a heating conduit.

FIG. 2 is an enlarged, end elevational view of the assembly shown in FIG. 1.

FIG. 3 is a fragmentary, end elevational view of the assembly shown in said FIG. 2, as installed in a building, the panels being shown in section.

FIG. 4 is a fragmentary, perspective view of the two sections forming my apparatus assembled around a conduit, the panels being omitted.

As illustrated, my heat transfer apparatus has two heat transfer sections 12 and 14 which are of duplicate construction. Each section has a contact holder portion 16 and 16a which, as shown, are arcuate in shape. Below each said holder portion is a joiner portion 18 and 18a which are shown extending slightly diagonally outward, and each has a hole 20 and 20a respectively to receive rivets 30 later described.

Bead receiving portions 22 and 22a extend laterally outward from one end of said joiner portions, and extending from the opposite end of the latter are connector portions 24 and 24a that terminate in diagonal portions 26 and 26a as shown. From the latter flat contact portions 28 and 28a extend angularly, which terminate my apparatus.

Said sections 12 and 14 are used together, as shown in said FIGS. 1 and 3, with two of said contact holder portions 16 and 16a in contact with and partly extending around a temperature modifying member. The latter is shown as a conduit C such as a well-known length of pipe through which hot water or steam, or a cooling medium may circulate, depending upon whether a heating or cooling effect is desired.

Beyond said conduit C said joiner portions 18 and 18a are preferably connected by pin members 30 shown as rivets, thus firmly keeping said holder portions 16 and

16a in contact with said conduit C. Said pin members 30 each extend through holes 20 and 20a as shown, and are spaced apart. They are put in place during an installation of my apparatus after said conduit C and holder portions 16 and 16a are in assembled position in contact with said conduit C.

My apparatus is shown held in position by hangers 32 that extend through slots 33 in said joiner portions 18 and 18a and are attached to a beam B as by a hook portion or by welding, or flat straps may be used.

My apparatus is used in combination with well-known metal pans or panels 34 having angular sides as shown. Each side has an outer extremity portion 36, adjoining which is a beaded portion 38 extending inwardly. Next to the latter is a connecting portion 40 that is beveled as at 42 where it joins the main face or flat surface 44 of the panel.

In use, opposed sides 34 of two different panels adjoin each other. Inwardly of and next to each of said adjoining sides are said two sections 12 and 14 of my apparatus, the holder portions 16 and 16a of which extend partly around and in contact with said conduit C which is above said panel sides 34. Said joiner portions 18 and 18a are just beyond said panel sides 34 and are fastened together by said pin members 30 as above explained. The beaded portions 38 of the panel sides extend into said outwardly extending portions 22 and 22a while said connector portions 24 and 24a are in contact with said panel connecting portions 40. Said contact portions 28 and 28a are parallel with and flat against said panel main face 44, hence heat from said conduits C, by conduction, next passes to said heat transfer sections 12 and 14 and finally from said contact portions 28 and 28a to the panel face portions 44.

What I claim is:

1. Heat transfer apparatus in combination with two panels, said panels each having a face portion and a side extending angularly therefrom, said sides respectively adjoining each other and each said side embodying an inwardly extending bead portion spaced respectively from said face portions, said apparatus embodying heat transfer means having two holder portions extending beyond said panel sides, two laterally outward extending bead receiving portions inwardly of said panel sides, said panel bead portions extending respectively into said bead receiving portions, and two contact portions extending angularly relative to said bead receiving portions and respectively contacting said face portions.

2. Heat transfer apparatus in combination with two panels as set forth in claim 1 in which said panels each has an outer extremity portion adjoining a said panel bead portion, and said heat transfer sections each has a joiner portion, parts of which are respectively laterally opposite said outer extremity portions.

3. Heat transfer apparatus in combination with two panels as set forth in claim 2 in which said panels each has an outer extremity portion adjoining a said panel bead portion, and said heat transfer sections each has a joiner portion, parts of which are respectively laterally opposite said outer extremity portions, and means connecting said joiner portions at a point beyond a said panel side.

4. Heat transfer apparatus in combination with two panels as set forth in claim 2 in which said panels each have a connecting portion extending respectively from said panel bead portions and said sections each have a connector portion extending from said bead receiving portion and are respectively opposite said panel connecting portions.

5. Heat transfer apparatus in combination with two panels, said panels each having a face portion and a side extending angularly therefrom, said sides respectively adjoining each other and each said side embodying an

extremity portion, a beaded portion adjoining the latter and extending inwardly therefrom, and a connecting portion adjoining said beaded portion and connected to said face portion, said apparatus embodying heat transfer means having two holder portions extending beyond said panel sides, two joinder portions extending from said holder portions and extending inwardly of and parallel with said panel outer extremity portions, two laterally outward extending bead receiving portions extending from said joinder portions and being inwardly of said panel sides, said panel bead portions extending respectively into said bead receiving portions, two connector portions extending from said bead receiving portions and extending inwardly of and being respectively opposite to and parallel with said panel connecting portions, and two contact portions extending angularly relative to said connector portions of said means and being respectively parallel with and in contact with said panel face portions.

6. A heat transfer member for use with two panels each having a face portion and a side extending angularly therefrom, said sides adjoining each other and each embodying an inwardly extending bead portion spaced respectively from said face portions, said heat transfer mem-

ber comprising two holder portions to extend beyond said panel sides, two laterally extending bead receiving portions to extend inwardly of said panel sides to receive said panel bead portions, two connector portions extending downwardly from said latter portions and two contact portions extending angularly relative to said connector portions to thereby make contact with said panel face portions.

7. A heat transfer member as set forth in claim 6, in which said connector portions extend downwardly from said bead receiving portions and thence diagonally outward until they reach said contact portions, said contact portions extending horizontally.
